MERCHANTISING PACKAGE FOR PINS

Benjamin L. Mink, Glenolden, Pa.

Application May 15, 1935, Serial No. 21,499

2 Claims. (Cl. 206—66)

This invention relates to an improved merchandising package for pins, particularly pins of a generally U-shape such as hairpins or "bobby" pins.

5 The objects of the invention are to provide a package of small size which can be readily carried in a pocket, purse or bag and from which the pins can be easily and readily removed when needed yet securely held in place so as not to 10 become lost or scattered loosely in the pocket, purse or bag.

Another object is to provide a merchandising package for pins of the character described in which the ends of the legs of the pins are hidden 15 or covered so as to prevent their catching upon other articles or projecting into the material of the pocket, purse or bag.

A still further object of the invention is to provide a merchandising package having the advantages just described which will be relatively inexpensive to manufacture.

The invention is illustrated in the accompanying drawing, wherein—

Figure 1 is a perspective view of my improved 25 package with the flap of the cover in open position, and

Figure 2 is a vertical cross section with the flap in closed position.

Examination of the figures will show that my 30 improved package includes a cover indicated as a whole by the reference character 3. This is made preferably of heavy paper or cardboard so that it can be readily folded to provide a back portion 4 and a front or flap portion 5, the lower end portion 35 of the back being folded or reverted to provide the recess 6. To close the flap portion 5 it is folded over along the line 7 and its free edge 8 is then slipped behind the free edge 9 of the reverted portion 10, as clearly shown in Figure 2.

40 The pins are mounted upon an insert 11 and in the present instance I have shown a plurality of bobby pins 12 which are passed through an opening 13 near the upper edge of the insert so that the pins may be said to straddle the insert.

45 The insert is then mounted in the cover by placing the edge opposite the opening 13 within the recess 6 and then securing it in position as by

the staple 14, and it will be noted that the ends 15 of the front legs of the pins, as mounted in the package, are hidden or protected by the reverted portion 10 so as to prevent their catching upon other articles or upon the material of the 5 pocket or container in which the package is carried should the flap portion 5 inadvertently slip out from behind the folded portion 10 so as to leave the pins exposed.

By mounting the pins in this way, i. e., with 10 the closed or base portion of the "U" projecting away from the recess 6 it is possible to readily remove one or more pins as desired simply by opening the flap and withdrawing a pin from the opening 13. Furthermore, by mounting the pins 15 astraddle in the opening 13 it is possible to more firmly hold the pins on the insert 11 than it would be were the pins simply mounted so as to straddle the upper edge of the insert.

It will be seen that my improved package is 20 exceedingly simple in construction and correspondingly inexpensive to manufacture while at the same time it provides a very convenient and secure package for the pins without in any way interfering with ready withdrawal of a pin when 25 desired.

What I claim is:—

1. A merchandising package for U-shaped pins comprising a cover having a back portion with a reverted or folded end portion forming a recess, a 30 front or flap portion the free edge of which is adapted to be slipped behind said folded end, and an insert having an opening with the pins astraddle therein, said insert being secured in the recess with the ends of the legs of the pins extending below the margin of said reverted portion.

2. A merchandising package for U-shaped pins comprising a cover having a back portion with a reverted or folded end portion forming a recess, 40 a front or flap portion the free edge of which is adapted to be slipped behind said folded end, and an insert having an opening with the pins astraddle therein, said insert being secured in the recess with the base or closed portions of the 45 U-shaped pins projecting away from the recess.
